WEFT REPLENISHING LOOM

Walter A. Patterson, Worcester, Mass., assignor
to Crompton & Knowles Loom Works, Worcester, Mass., a corporation of Massachusetts

Application December 22, 1943, Serial No. 515,203

16 Claims. (Cl. 139—232)

This invention relates to improvements in weft replenishing looms and it is the general object of the invention to provide a loom wherein a shuttle can be replenished with bobbins drawn from a plurality of stacks of bobbins.

In prior Patent No. 2,312,146 issued to Brouwer and myself there is shown a four-cell magazine adapted for the replenishment of two shuttles. The stacks and their bobbin releasers are arranged in pairs, one pair for one shuttle and another pair for the other shuttle, and each pair is associated with a lever which is rocked when one or another of the corresponding releasers is raised. Rocking of this lever operates with other mechanism to cause an alternation in the order in which bobbins are drawn from the stacks of the pair.

In magazines of the type to which my invention more particularly relates the bobbin releaser is raised by the rocking of a selector when a depleted shuttle is at the magazine end of the loom. The shuttle is then picked to the opposite side of the loom and if it goes out of action there will be a corresponding shift of the selector so that the latter will not register with the previously raised releaser. Upon return to action of the depleted shuttle, however, the selector will register with the raised releaser and the latter will be depressed to deliver a bobbin from the associated stack. In the patent mentioned the lever is rocked by up motion of the releaser and therefore at a time prior to the movement of the selector which lowers the releaser for bobbin delivery. In order to take account of the lapse in time between the rising and falling of the releaser, the previously mentioned patent uses pivoted lugs on the releasers and also a broadened finger on the selector capable of engaging two depressing releaser lugs at the same time. This broadened finger, however, interferes with operation of the magazine in its more usual setting for the replenishment of four different shuttles.

It is an important object of my present invention to provide a rocking lever somewhat similar to that shown in the aforesaid patent but rock it on the downward motion of a releaser. By this arrangement any mechanism which alters the registry of the selector with the releasers will not be brought into action until after the selector has been able to return to registry with a releaser which it previously raised and the usual type of finger on the selector can be employed.

The bobbin releaser for the ordinary stationary magazine is provided with a dog normally idle but moving to operating position when the releaser rises and then acting upon descent of the releaser to rock a shaft to set the magazine for transfer. It is another object of my present invention to modify the dog in such a way

that it can rock the aforesaid lever upon descent of the releaser. In this way it is not necessary to add any additional moving part to the releaser and the spring on the releaser which controls

5 the ordinary dog can also be used for the new part which rocks the lever.

The rock shaft mentioned has secured thereto a shelf or extended arm which ordinarily lies above the bottom of the dog when the releaser is down.

10 As the releaser rises the dog tends to move toward operative position but is restrained from doing so by the shelf until the releaser nears the upper end of its movement. It is another object of my present invention to provide the dog with a hook extension which in its upward movement with the releaser is held away from the aforesaid rocking lever due to engagement of the dog with the shelf. The hook moves to a position above the lever before the bottom of the dog is finally clear of the shelf, and for this reason there is no engagement between the hook and the lever which would cause wearing of these parts.

With these and other objects in view which 25 will appear as the description proceeds, my invention resides in the combination and arrangement of parts hereinafter described and set forth.

In the accompanying drawings, wherein a convenient embodiment of my invention is set forth,

30 Fig. 1 is a side elevation of a four-cell stationary magazine as seen from the center of the loom and provided with my invention,

Fig. 2 is a vertical section on line 2—2 of Fig. 1,

35 Fig. 3 is a diagrammatic view showing the relation of the shuttle boxes, lay and selector used with my invention,

Figs. 4 and 5 are enlarged side views of those 40 parts of the invention shown in Fig. 1 which effect alternate delivery of bobbins from the two pairs of stacks,

Fig. 6 is a diagrammatic view showing the 45 relationship between the bobbin releaser, its dog, the setting shelf, and the rocking lever when the releaser is down,

Fig. 7 is a view similar to Fig. 6 but showing the relationship as it exists when the releaser is at or near the upper end of its movement,

50 Fig. 8 is an enlarged vertical section on line 8—8 of Fig. 4, showing the friction device by which the rocking lever is held in the two positions to which it is moved, and

Fig. 9 is a detailed front elevation of the front stop member.

55 Referring to Figs. 1 and 3, the loom frame 10 supports a four-stack stationary magazine M over the lay L having a gang G of shuttle boxes at the left end and a single box B under the magazine. The magazine has four stacks of reserve bobbins indicated at 11, 12, 13 and 14,

stack 11 being at the front of the magazine. Each stack has associated therewith a bobbin releaser or vertical slide, these releasers being indicated at 15, 16, 17 and 18. The bottom of each releaser cooperates with a cradle 19 which rocks in one direction to receive a bobbin from the associated stack and then rocks in the opposite direction to discharge the bobbin so that it can move to transfer position under a transfer arm 20.

The magazine is provided with a stack selector 21 including in its construction a shaft 22 and a casting 23 from which extend front and back fingers 24 and 25, respectively. The selector is connected by rod 30 to an actuator lever 31 mounted on the upper end of a vertically reciprocating rod head 32 under control of a pin 33. The weft detector D detects the condition of weft on alternate beats of the loom when a shuttle is in box B and if sufficient weft for continued weaving is present pin 33 is moved forwardly out of the path of lever 31 as the rod head 32 descends and the rod 30 and selector remain stationary. If, on the other hand, the detector indicates weft exhaustion the pin 33 remains in the path of lever 31 and upon descent of head 32 the rod 30 is pulled down to rock the selector in a counterclockwise direction as viewed in Fig. 2, thereby raising its fingers 24 and 25. This rocking of the selector occurs only when the detector indicates weft exhaustion. At some time during the following pick of the loom, preferably after the shuttle gang G has completed its shift, rod head 32 rises and acts through lever 31 to give an upward thrust to rod 30 for the purpose of rocking the selector 21 in a clockwise direction as viewed in Fig. 2 to depress the fingers 24 and 25. This last named rocking of the selector occurs every other pick of the loom.

In addition to the rocking movement already described the selector also has longitudinal movements imparted to it by mechanism connected in one way or another to move in timed relation with the gang of shuttle boxes G shown in Fig. 3. This gang has top and bottom box cells 35 and 36, respectively, for shuttles S' and S², respectively. By mechanism not shown but well understood the boxes are shifted with respect to the shuttle race 37 on the lay L. In a convenient manner of operating the loom to take advantage of my invention shuttle S' will be active for two consecutive picks and will then move to inactive position while shuttle S² is active for two picks, after which shuttle S' will return to action for another pair of picks, etc.

As shown diagrammatically in Fig. 3, a connector 40 is attached to the gang G and leads across the loom to the magazine side and then upwardly for attachment to lever 41 mounted on a pivot 42 fixed to the magazine frame. An upright arm 43 of lever 41 engages a collar 44 on the rod 22 and is the means by which longitudinal motion is imparted to the selector 21. A spring 45 connected at one end to lever 41 and at the other end to a fixed part of the magazine exerts a force tending to turn the lever in a clockwise direction as viewed in Fig. 1 and move the selector 21 to its frontmost position. The selector is of the usual type and its two fingers 24 and 25 are capable of cooperating with the releasers one at a time first to raise and then lower them as already described, the selection thus effected being determined by the longitudinal position of the selector which in turn is due partly to the control exercised by the gang G through connector 40 and partly to mechanism to be described.

The top part of the magazine has a rock shaft 50 provided with a shelf 51 which extends toward the releasers. A lever 52 on shaft 50 is connected to a depending rod 53 by means of which a transfer latch 54 is raised in the path of the lay carried transfer bunter 55 when shaft 50 is turned in a clockwise direction as viewed in Fig. 2. A second arm 60 also secured to shaft 50 is attached to a depending rod 61 connected to the shuttle position detector 62 conveniently pivoted on the magazine. When shelf 51 moves to rock shaft 50 in a clockwise direction as viewed in Fig. 2 it effects setting of the magazine for a replenishing operation by moving the transfer latch to transfer position and lifting rod 61 to move the shuttle position detector 62 rearwardly toward the lay L. Because of the function of shelf 51 just described it may be considered as constituting a setting member for the magazine.

Under normal conditions the shelf 51 is raised as shown in Fig. 2. The shelf is depressed by means carried by the releasers, each releaser for this purpose having a dog 65 pivoted at 66 to the associated releaser and having a foot 67 to receive the downward thrust of a small compression spring 68 extending from a head 69 at the upper end of the releaser. The foot 67 moves vertically through a slot 70 in the magazine frame F and the bottom of slot 70 engages the foot 67 during descent of the releaser to rock the dog away from shaft 50 and shelf 51, but when the releaser rises the foot 67 moves away from the bottom of the slot 70 and spring 68 tends to turn dog 65 toward the shaft 50.

Fig. 6 shows the normal relation of the dog 65 and the shelf 51, from which it will be seen that the bottom of the dog extends considerably below the shelf and is held in idle or inactive position. As the releaser rises the spring 68 forces the dog 65 against the shelf 51 until the bottom of the dog reaches the top of shelf 51, see full lines Fig. 7, after which continued upward movement of the releaser permits the spring 68 to project the dog 65 to its working position where it overhangs the shelf 51, as shown in dotted lines in Fig. 7. Thereafter, upon descent of the releaser the dog 65 engages the shelf and rocks shaft 50 in a clockwise direction, Fig. 2, for purposes already described. On the forward beat of the lay accompanying transfer the shuttle position detector 62 is struck and moved forwardly by the lay to exert a downward pull through rod 61 on arm 60 to rock shaft 50 and shelf 51 back to the normal full line position shown in Fig. 6.

The matter thus far described except as indicated hereinafter is of common construction and operates in the usual manner. For further understanding of the mechanism reference may be had to prior Patent No. 1,030,748. As a matter of practical convenience to insure correct movement on the part of the releasers each of the latter is provided with a wedge 73 to cooperate with a spring plunger 74 as described in patent to Chevrette No. 1,510,765. Also, each releaser has a top lug 75 to be raised by one or another of the fingers 24 and 25 and has also a bottom lug 76 to be lowered by one or another of the fingers on the selector.

The mechanism thus far described is of the type which would permit the use of four shuttles each having distinctive weft to be replenished by reserve bobbins drawn from the appropriate stack in the magazine. In modifying this structure so that it can efficiently replenish each of two shuttles I assign the front pair of stacks 11 and 12

to shuttle S' and the back pair of stacks 13 and 14 to shuttle S² and furthermore provide mechanism by which successive replenishing operations occurring with respect to either pair will draw bobbins alternately from the stacks of that pair. For an understanding of this mechanism reference may be had more particularly to Figs. 1 and 3 to 6. Since these mechanisms, one for each pair of stacks, are very similar I will give a detailed description of one of them and then indicate the differences which exist between it and the mechanism for the other pair of stacks.

Pivoted to the upper forward part of the magazine is a stop controlling lever 80 having front and back arms 81 and 82, respectively, each having its upper edge concave as at 83. The stud 84 on which the lever is pivoted is surrounded by a short compression spring 85, see Fig. 8, located between the head of the stud and the lever and serving to exert a frictional force on the lever tending to hold it on the magazine frame in any position to which it is moved. Extending from arm 81 is a rod 86 which receives the upper slotted end 87 of a depending rod 88 the lower end of which is secured to a stop 89. The stop 89 is provided with spaced arms 90 which straddle the rod 22 and is provided also with a stop element 91 adapted for engagement with the casting 23 when in down position but lying above the casting when the stop is in raised position. Releasers 15 and 16 have their dogs 65 formed with upwardly extending hooks 95 and 96, respectively. These hooks have heads 97 adapted to enter the concave upper edges of the corresponding arms of lever 80, hook 95 cooperating with arm 81 and hook 96 cooperating with arm 82.

Considering transferring operations involving the front pair of stacks, and assuming that arm 81 is in high position so that stop 89 has its stop element 91 above casting 23, and further assuming that shuttle S' is active, spring 45 will move the selector 21 to its extreme forward position with finger 24 in register with releaser 11. At this time the releasers are down, but if shuttle S' should indicate exhaustion of weft upon arrival under the magazine the selector will be rocked and raised releaser 15 as already described. The head 97 is ordinarily below the lever arm with which it will cooperate, and as the releaser 15 rises the head 97 will have a slight motion toward arm 81 until dog 65 engages shelf 51. The head 97 therefore rises without engaging arm 81, the lower end of its hook rising to an elevation above arm 81, see full lines Fig. 7, before the bottom of dog 65 is projected to working position by spring 68 due to the fact that shelf 51 is acting temporarily as a stop for the dog 65. When this latter movement of the dog occurs the head 97 moves over the arm 81, moving from the full to the dotted line position shown in Fig. 7. Shuttle S' is then picked to the opposite side of the loom, and the gang G shifts to move the selector 21 rearwardly. Upon return of shuttle S' to activity the selector returns to registry with releaser 15 and when finger 24 is depressed as already described the dog 65 will rock the setting member or shelf 51 and the head 97 of hook 95 will rock lever 80 in a clockwise direction as viewed in Fig. 4, thus lowering rod 86 and permitting the stop 89 to fall on casting 23. When the replenished shuttle S' again reaches the gang G and the latter shifts, the selector 21 will again be moved rearwardly, whereupon the stop element 91 will have a further falling movement in the path of the selector and when the latter attempts

to return to its extreme forward position under action of spring 45 it will be engaged by the stop and held in such position as to cause its finger 24 to register with releaser 16. The stop 89 during this action is held against movement to the right as viewed in Fig. 3 by bearing 100 on the magazine frame through which the rod 22 slides.

The next time shuttle S' is replenished slide 16 will rise and its hook 96 will effect down motion of arm 82 to effect reverse motion of the lever 80 for the purpose of lifting the stop 89 out of the path of the selector. The latter is therefore free to register with releaser 15 when shuttle S' returns to box B. In this way the stacks 11 and 12 alternately supply bobbins from successive transfers from the front pair of stacks.

The rear pair of stacks is associated with a second lever 105 having front and back arms 106 and 107, respectively. Lever 105 is pivoted on a stud 108 similar to stud 84 and has a rod 109 receiving the upper slotted end 110 of a depending rod 111 similar to rod 88 and having connected at the lower end thereof a stop 112 having arms 113 to straddle shaft 22 and having also a stop element 114 for engagement with the rear end of casting 23. A second bearing 115 for shaft 22 limits movement of the stop 112 to the left as viewed in Fig. 1.

The dogs of releasers 17 and 18 are provided with hooks 120 and 121, respectively, similar to hooks 95 and 96 and each having a head 97. These hooks and heads are formed as parts of the shelf engaging dogs on the rear pair of releasers and operate in the same general manner as that described in connection with releasers 15 and 16.

Assuming that shuttle S² is active and that the rear end 107 of lever 105 is in high position, the stop 112 will be above casting 23 and since gang G is up at this time, the downward pull of connector 40 against the action of spring 45 will move the selector to its extreme rear position with finger 25 in register with releaser 18. When indication of weft exhaustion is given by shuttle S² the rearmost releaser will rise and upon descent its hook 121 will rock lever 105 in a clockwise direction as viewed in Fig. 5 to effect down motion of the stop 112. When the selector 21 moves forwardly incident to a shift of gang G when shuttle S² enters box 36, stop element 114 will fall in alignment with casting 23 and bearing 115. Upon return to action of shuttle S² a downward pull on connector 40 moves the selector rearwardly until it engages stop element 114 with finger 25 in register with releaser 17. After this engagement, however, the gang G continues to move and it is necessary to provide a yielding element between the gang and the selector. For this purpose I prefer to use a spring 125 in connector 40 stronger than spring 45. Ordinarily this spring 125 is strong enough to move the selector rearwardly against the action of spring 45, but as the gang of shuttle boxes continues to move subsequent to arresting of the selector by stop 112, spring 125 will expand to permit finger 25 to remain registered with releaser 17.

The next time shuttle S² is replenished the hook 120 will engage arm 106 to lower the latter and simultaneously raise the stop 112 to non-stopping position to permit the selector 21 to move to its rearmost position.

From the foregoing it will be seen that I have provided simple mechanism by which each of two shuttles can be replenished from bobbins drawn from a pair of stacks and that successive

drawings of bobbins from any pair involve the stacks of the pair alternately. In this way the stacks of the pair become depleted uniformly and the full capacity of the magazine can be utilized for replenishment of the shuttles. It will also be seen that the alternation in the order in which the bobbins are released is effected by an upward extension from the ordinary shelf depressing dog on the releasers, thereby making unnecessary a second moving part on the releasers for accomplishing this result. Also, the shelf 51 which acts as a setting member to set the magazine for transfer, serves as a stop for the dog 65 and its hook during the greater part of the upward motion of the associated releaser and the head 97 rises to a level above the arm of the rocking lever with which it is to cooperate before the dog is free from the shelf. Furthermore, it will be seen that I have provided a novel form of bobbin releaser to the upper end of which is pivoted a member part of which is the usual dog and another part of which cooperates with the rocking lever to effect delivery of bobbins alternately from the associated pair of stacks. The levers 80 and 105 and their stops 89 and 112, respectively, may be considered as control mechanisms for the selector, while the levers are controllers for their respective stops.

Having thus described my invention it will be seen that changes and modifications may be made therein by those skilled in the art without departing from the spirit and scope of the invention and I do not wish to be limited to the details herein disclosed, but what I claim is:

1. In a bobbin releaser for a weft replenishing loom having a magazine setting member and a stack selector stop operating member, an element movably mounted on said releaser having a part for cooperation with the setting member and having a second part for cooperation with the stop operating member, and resilient means carried by said releaser tending to move said parts toward positions for cooperation with their respective members.

2. In a bobbin releaser for a weft replenishing loom having a magazine setting member and a stack selector stop operating member, a spring carried by said releaser, and a three armed element pivoted on said releaser, one arm for said setting member and the second arm for said stop operating member and the third arm cooperating with said spring to move the first and second arms toward positions for cooperation with their respective members.

3. In a bobbin releaser for a weft replenishing loom having a magazine setting member and a stack selector stop operating member, said releaser having an elongated body, an element pivoted on said body and having a dog for said setting member extending downwardly along said body and a hook for said stop operating member extending upwardly from said body, and a spring carried by said body tending to move said dog and hook toward positions for cooperation with their respective members.

4. A weft replenishing mechanism bobbin releaser for cooperation with a setting member and a bobbin stack selector stop operating means, said releaser comprising a body provided with an element having a depending dog for the setting member and a hook for the bobbin stack selector stop operating means extending upwardly from the dog, a pivotal connection between said body and element intermediate said dog and hook, and

a spring carried by the body tending to move the element around said pivotal connection.

5. A weft replenishing mechanism bobbin releaser for cooperation with a setting member and a bobbin stack selector stop operating means, said releaser being provided with a pivot, an element mounted for angular movement on said pivot having a dog on one side of said pivot for the setting member and a hook on the opposite side of said pivot for the bobbin stack selector stop operating means, and a spring carried by the releaser tending to turn the element around said pivot.

15 6. A weft replenishing mechanism bobbin releaser for cooperation with a setting member and a bobbin stack selector stop operating means, said releaser carrying a spring and an element pivoted on said releaser engaging said spring and having a dog for the setting member and a hook on the dog for the bobbin stack selector stop operating means.

20 7. An operating unit for the setting member and bobbin stack selector stop mechanism of a weft replenishing magazine, said unit having a dog for the setting member and a hook for the stop mechanism.

25 8. An operating unit for the setting member and bobbin stack selector stop mechanism of a weft replenishing magazine, said unit having a bearing for pivotal support thereof, a dog for the setting member on said unit on one side of said bearing, and a hook for said stop mechanism on said unit on the opposite side of said bearing.

30 9. An operating unit for the setting member and bobbin stack selector stop mechanism of a weft replenishing magazine, said unit having a bearing for pivotal support thereof, and three arms radiating from said bearing, one arm being a dog for said setting member, the second arm being a hook for said stop mechanism, and the third arm being means for turning the unit about the bearing.

35 10. An operating unit for a bobbin releaser having a spring and adapted for use on a weft replenishing magazine having a setting member and a bobbin stack selector stop mechanism, said unit comprising a dog for said setting member, a hook for said stop mechanism, and an arm for said spring.

40 11. In a weft replenishing loom having a setting member movable from normal to setting position to set the loom for a replenishing operation, the loom operating with a selector under control of a stop and moving into registry with a plurality of bobbin stacks, one at a time, depending upon the position of the stop, a bobbin releaser for each stack, each releaser having an initial movement from normal to indicated position and having a subsequent return movement from indicated to normal position incident to a replenishing operation involving the releaser, a controller for said stop controlling the position thereof to determine with which releaser the selector shall register, an operating element movably mounted on each releaser and having a dog and a hook thereon, and a spring on each releaser tending to turn the corresponding element in a direction to move the dog toward said setting member and move the hook toward said controller, each spring during the initial movement of the associated releaser moving the corresponding dog against said setting member to hold the hook spaced from the controller until

45 55 60 65 70 75

the releaser nears the end of the initial movement thereof, whereupon the spring moves the dog over the setting member and moves the hook over said controller, the releaser when having the return movement thereof causing the dog to move the setting member to setting position and causing the hook to operate said controller.

12. In a weft replenishing loom having a setting member movable from normal to setting position to set the loom for a replenishing operation, the loom operating with a selector under control of a stop and moving into register with a plurality of bobbin stacks, one at a time, depending upon the position of the stop, a bobbin releaser for one of said stacks having an initial movement from normal to indicated position and a subsequent return movement from indicated to normal position incident to a replenishing operation involving bobbins drawn from said one stack, a controller for said stop controlling the position thereof to determine with which stack said selector shall register, an operating member pivoted on said releaser and having an element to operate said setting member and a second element thereon to operate said controller, and a spring on the releaser tending to turn the member to move the first element toward said setting member and move the second element toward said controller, said setting member engaging the first element during the greater part of the initial movement of said releaser to cause the second element to move along a path spaced from said controller, the last part of the initial movement of the releaser moving the first element out of engagement with the setting member, whereupon the spring moves said first element into operating position relatively to the setting member and moves the second element into operating position relatively to the controller, the releaser on the return movement thereof causing the first element to move the setting member to setting position and causing the second member to operate said controller.

13. In a weft replenishing loom having stacks of reserve bobbins and bobbin stack selector means and a controller for a selector means stop the position of which determines with which stack the selector shall register, a bobbin releaser for one of said stacks having an initial movement and a return movement incident to a replenishing operation involving said one stack, a member on said releaser having an operating element for the controller, a spring on said releaser tending to move said operating element toward said controller, and means cooperating with said member and overpowering said spring during the greater part of the initial movement of said releaser causing said element to move along a path spaced from said controller, said member moving beyond said means as the releaser nears the end of the initial movement thereof and the spring thereupon moving the operating element laterally of said path into operating position with respect to the controller, said releaser on the return movement thereof causing said element to operate the controller.

14. In a weft replenishing mechanism having a frame supporting a plurality of stacks of reserve bobbins, the loom having a selector to register with said stacks, one at a time, a selector control mechanism including a lever pivoted on said frame to determine with which stack said selector shall register, a bobbin releaser having an initial and a subsequent return movement in-

cident to a replenishing operation of the mechanism, a pivoted element on said releaser having a hook for said lever, means tending to move the hook toward said lever, and a stop for said element effective during the greater part of the initial movement of said releaser to cause the hook to traverse a path laterally displaced from said lever, the releaser upon completion of the initial movement thereof moving said element away from said stop, whereupon said means moves the hook laterally of said path into operating position with respect to the lever, and the releaser on the return movement thereof causing said hook to engage and rock said lever for the operation of said control mechanism.

15. In a weft replenishing mechanism having a frame supporting a plurality of stacks of reserve bobbins, said mechanism having a selector movable into register with said stacks, one at a time, control mechanism including a lever pivoted on said frame to determine with which stack said selector shall register, a bobbin releaser for one of said stacks having a rising and a subsequent descending movement incident to a replenishing operation involving said one stack, an element pivoted on said releaser having a hook for said lever, a resilient device tending to move the hook toward said lever, and a stop for said element to prevent movement of the latter by said resilient device, said stop cooperating with said element during the first part of the rising movement of said releaser to cause the hook to move along a path laterally displaced from said lever and said releaser during the latter part of the rising movement thereof moving said element out of engagement with said stop after said hook has been moved to a level above the level of the lever, whereupon said resilient device moves the hook over the lever, and the releaser during the descending movement thereof causing said hook to engage and rock said lever to operate said control mechanism.

16. In a weft replenishing mechanism having stacks of reserve bobbins and operating with a setting member movable to set the mechanism for a replenishing operation and having a selector moving into register with said stacks, one at a time, positioning mechanism for said selector including a control member and operative when the latter moves to determine with which stack said selector shall register, a bobbin releaser for one of said stacks having initial and return movements incident to a replenishing operation involving said one stack, movable means on said releaser having an operating element for said setting member and a second operating element for said control member, and resilient means on said releaser tending to move each element toward operative position relatively to the corresponding member, said setting member engaging the operating element thereof during the first part of the initial movement of said releaser to prevent said resilient means from moving the second operating element into operating relation with the control member, said releaser during the latter part of the initial movement thereof moving said first operating element out of engagement with said setting member, whereupon said resilient member moves each operating element into position for operation of the member corresponding thereto, and said releaser on the return movement thereof causing operation of each member by the element corresponding thereto.
